UNITED STATES PATENT OFFICE.

JULIUS M. FARMER, OF NEW YORK, N. Y., ASSIGNOR, BY DIRECT AND MESNE ASSIGNMENTS, OF PART TO CHARLES FREDERICK FOGG, OF SAME PLACE, AND HORACE C. STROUT, OF BROOKLYN, NEW YORK.

ROTARY ENGINE.

SPECIFICATION forming part of Letters Patent No. 394,684, dated December 18, 1888.

Application filed January 31, 1888. Serial No. 262,492. (No model.)

To all whom it may concern:

Be it known that I, JULIUS M. FARMER, of the city, county, and State of New York, have invented a new and Improved Rotary Engine, 5 of which the following is a full, clear, and exact description.

The object of the invention is to provide a new and improved rotary engine which is simple and durable in construction and very 10 effective in operation, utilizing the steam to the fullest advantage, at the same time being easily reversed.

The invention consists of a revolving disk secured to the main driving-shaft and carrying 15 one, two, or more sets of cylinders, each set consisting of two cylinders placed diametrically opposite each other and connected with each other by a piston-rod carrying a cross-head held to slide on a fixed pin arranged eccentrically to the said revolving disk, and of 20 a steam-chest formed on the bearing of the disk and connected by suitable ports with the sets of steam-cylinders.

The invention also consists of certain parts 25 and details and combinations of the same, as will be fully described hereinafter, and then pointed out in the claims.

Reference is to be had to the accompanying drawings, forming a part of this specification, 30 in which similar letters of reference indicate corresponding parts in all the figures.

Figure 1 is a front elevation of the improvement. Fig. 2 is a sectional end elevation of the same on the line *x* *x* of Fig. 4. Fig. 3 is a like view of the same on the line *y* *y* of Fig. 4. Fig. 4 is a sectional end elevation of the improvement on the line *z* *z* of Fig. 1. Fig. 5 is a side elevation of the disk-bearing and steam-chest; and Fig. 6 is a sectional elevation on the line *w* *w* of Fig. 5, showing part 40 of the disk in section.

On a suitably-constructed frame, A, is mounted to rotate the main driving-shaft B, provided with a driving-pulley, C, for transmitting the rotary motion of the shaft B. The front end of the shaft B is provided with a head, B', having lugs B² fitting in corresponding recesses formed in the front end of the

disk D, so that when the latter is rotated it also rotates the shaft B. The disk D is 50 mounted to turn on a conical hub, E, secured to one of the standards of the frame A, and on the top of the said conical hub E is formed a steam-chest, F, provided with a steam-inlet pipe, G, and also provided with a slide-valve, 55 H, adapted to open and close alternately the live-steam ports *a* and *b*, extending inward in the hub E from the interior of the steam-chest F. A suitable mechanism, I, is used for moving the said slide-valve H over the respective ports *a* and *b* whenever the operator desires to reverse the engine. It is understood that when one of the ports *a* or *b* is opened the other port is closed, and vice versa.

On the disk D are secured one, two, or more 60 sets of cylinders, J J' and K K', the cylinders of each set being placed diametrically opposite each other, as is shown in Figs. 1 and 4. In the cylinders J J' operate the pistons L and L', respectively, connected with each 65 other by a piston-rod, L², carrying in its middle a cross-head, L³, provided with a slot, L⁴, extending at right angles on each side of the piston-rod L². The cylinders K and K' are provided with pistons N and N', respectively, 70 connected with each other by piston-rod N², also provided in its middle with a cross-head, N³, having a slot, N⁴, extending at right angles to the piston-rod N². Thus the two cross-heads L³ and N³ are held at right angles to 75 each other—one in front of the other—so that a pin, O, extends into the slots L⁴ and N⁴ of the said cross-heads L³ and N³. The pin O is secured to a standard, P, fastened on the main frame A, and the said pin O is held eccentric 80 to the main driving-shaft B, the distance between the axes of the shaft B and the pin O being equal to one-half of the stroke of each of the cylinders J J' and N N'.

On the shaft B is coiled a spring, R, one 85 end of which rests on the hub E, its other end pressing against a collar, S, secured on the main shaft B. The spring R exerts a pressure against the shaft B in the direction of the arrow *u'*, so that the disk D is firmly held on 90 its conical bearing or hub E, thereby forming 95

a steam-tight joint between the said disk D and its bearing E.

In the outer end of the cylinder J is formed a port, d, which connects permanently with a channel, e, formed in the disk D, and extending to a port, d', formed in the inner end of the cylinder J'. A port, f, is formed in the inner end of the cylinder J, and connects permanently with a channel, g, formed in the disk D and extending to a port, f', formed in the outer end of the cylinder J'. The channels e and g extend on opposite sides of the hub or bearing E; as illustrated in Figs. 2 and 3.

15 In the outer end of the cylinder K is formed a port, h, which registers permanently with a channel, i, formed in the disk D and extending to a port, h', formed in the inner end of the cylinder K'. In the inner end of the cylinder K is formed a port, j, which connects permanently with the channel k, leading to a port, j', formed in the outer end of the cylinder K'. The channels i and k extend at opposite sides of the hub E and at right angles to the channels e and g, as illustrated in Figs. 1 and 3. The channel e leads into a U-shaped channel, e', opening at both ends into the conical aperture D', which forms the bearing of the disk D on the hub E. The other channels, g, i, and k, open into like U-shaped channels g', i', and k', also leading into the conical aperture D' of the disk D.

The U-shaped channels e' g' and i' k' are arranged opposite each other, as shown in Fig. 2, and the end openings of each of the said channels are alternately opened and closed by the slides e², g², i², and k², respectively, so that when one of the end openings of the respective channel is open the other one is closed by its corresponding slide, and vice versa. The open end of each U-shaped channel e', g', i', or k' registers alternately at each revolution of the disk D with the open live-steam ports a or b and with the exhaust-port c, formed in the hub E and leading to an exhaust-pipe, c', extending to the outside in the usual manner. The live-steam port a extends from the steam-chest F and opens into the periphery of the hub E at a' near the inner end of the said hub E, and the other live-steam port b extends from the steam-chest F and opens into the periphery of the hub E at b', near the outer end of the said hub. The end openings a' and b' of the live-steam ports a and b are placed a short distance on one side of the horizontal central plane of the hub E, as is plainly shown in Figs. 2 and 3—that is, the end opening a' of the live-steam port a is above the middle line of the disk D and the end opening b' of the live-steam port b is a like distance below the middle line.

65 The exhaust-port c opens at c² into the periphery of the hub E, near the inner end of the latter, in a vertical plane with the end opening a' of the steam-port a. From the exhaust-port c, near its end opening c², extends a continuation of the exhaust-port c, which

opens into the periphery of the hub E at c³, which is in a vertical plane with the end opening b' of the live-steam port b.

70 The operation is as follows: As shown in Fig. 4, the live-steam port b is closed by the slide-valve H, while the live-steam port a is open, so that the steam entering the steam-inlet pipe G passes through the steam-chest F 75 and passes into the port a through the same and out of the latter at its opening a'. The slides e², g², i², and k² are in their outermost position, so that the innermost end openings of the U-shaped channels e', g', i', and k' 80 register with the said end opening a', whereby the live steam can pass alternately into the channels e, k, g, and i, thus supplying the respective cylinders J' K K' with live steam. When the channel g' registers with the end 85 opening a', the live steam passes into the channel g, and from the latter passes simultaneously to the ports f and f' in the cylinders J J', whereby the piston L is moved outward and the piston L' is moved inward, so 90 that the piston-rod l² slides across the face of the disk D in the direction of the arrow t', whereby the cross-head L³ forms a fulcrum-point for the disk D at the pin O, so that the said disk is rotated in the direction of the arrow s' and a consequent rotary motion is imparted to the main shaft B, which transmits its rotary motion to the machinery to be driven. As the disk D revolves, the inner end of the U-shaped channel g' is cut off from the end 100 opening a' of the live-steam port a, and when the said disk D has made one-half of a revolution and the pistons L and L' are at their outermost and innermost position then the open end of the U-shaped channel g' registers with the end opening c² of the exhaust-port c, so that in the next half-revolution of the disk D the steam in the cylinders J and J' can exhaust on the return-stroke of the pistons L and L' through the ports f and f' 110 and the channel g, through which the steam originally entered. As soon as the channel g has cut off from the end opening a' of the live-steam port a, the next following channel, k, connects by the open end of its U-shaped 115 channel k' with the said opening a' of the live-steam port a, so that the live steam from the steam-chest F passes into the channel k and to the inner end of the cylinder K and the outer end of the cylinder K', the respective pistons N and N' being in the same relative position as described in reference to the cylinders J and J', and as shown in Fig. 4. The steam will thus act on the pistons N and N' and force the same outward and inward, 125 respectively, whereby a new impulse is given to the disk D in the direction of the arrow s' by the action of its cross-head N³ on the eccentric-pin O. During one-half of a revolution the steam entered through the channel k into the cylinders K K' expanded, forcing the pistons N and N' to the end of their stroke, after which the channel k, after its U-shaped 130 connecting-channel k', will register with the

end opening c^2 of the exhaust-channel c , so that on the return-stroke of the piston N and N' the steam will be exhausted through the same channel k , the respective ports j, j' , and 5 the exhaust-port c . It is understood that the connection of the open end of the channel g' and the channel k' with the end opening a' of the live-steam port A takes place during one-quarter of a revolution of the disk D . During 10 the next quarter-revolution of the disk D the open end of the U-shaped channel e' will connect in the same manner as above described in relation to the channels g' and k' with the open end a' of the live-steam port a , so that the steam enters in the channel e , and 15 from the latter passes to the ports d and d' at the outer or inner ends of the cylinders J and J' , respectively. As the pistons L and L' in the cylinders J and J' have traveled to their 20 outer or inner ends, respectively, the steam entering through the said channel e and the ports d and d' will cause the return-stroke of the return-pistons L and L' , as above mentioned. This return-stroke takes place during 25 one-half revolution of the disk D from the time that the steam-port g took steam from the live-steam port a , as above mentioned. The channel e' , for cutting off from the end a' of the live-steam port a , makes one-half of 30 a revolution, and then connects with the end openings c^2 of the exhaust-channel c . When the disk D has made one-quarter of a revolution, beginning at the time when the channel e' registered with the end opening a' of the 35 live-steam port a , then the open end of the U-shaped channel i' registers with the open end a' of the live-steam port a , so that steam from the steam-chest F passes into the channel i , and through the outer and inner ends, 40 respectively, of the cylinders K and K' in the same manner as above described in reference to the cylinders J and J' . Thus it will be seen that each set of cylinders, after taking steam with one channel at the end opening, a' , of the 45 live-steam port a makes one-half of a revolution before the said respective channel connects with the exhaust-channel c , and then at this time the other channel of the same set of cylinders connects with the live-steam port, 50 thus causing a return-stroke of the respective piston of the said set of cylinders. As the two sets of cylinders J, J' and K, K' are placed at right angles to each other, it will be seen that a new impulse is given to the disk D at 55 every quarter-revolution of the same. It will further be seen that the steam exerts its pressure on the two pistons of each set of cylinders at the same time, and, as the said two pistons by their piston-rod and cross-head and the 60 eccentric-pin O act on the disk D in one direction, the latter is turned with twice the force that would be used if only one cylinder had been employed.

When the operator desires to reverse the 65 engine, he turns the valve mechanism I so that the slide-valve H closes the live-steam port a and opens the live-steam port b . The

live steam now enters from the steam-chest F into the port b and passes to its end opening, b' , where it comes in contact with the outer 70 end of the respective slide e^2, k^2, g^2 , or i^2 , (see Fig. 6,) so that the said slide is moved inward by the pressure of the steam, thereby closing the former open end of the U-shaped channel e', k', g' , or i' , and opening the other end 75 of the said respective channel. As the open ends a' and b' of the respective ports a and b are above and below the horizontal middle line of the disk D , as before described, and shown in Fig. 5, it will be seen that the live 80 steam now passing from the live-steam port b through the open end b' of the respective channels e', k', g' , and i' will cause the disk D to rotate in the inverse direction of the arrow s' .
85

The above operation is repeated, with the only difference that the live steam passes through the port b , its end opening, b' , and into the respective channels $e', k',$ and i' , and the exhaust takes place through the same 90 channels, registering with the open end c^3 of the exhaust-channel c . As the slides e^2, k^2, g^2 , and i^2 are now in their innermost position, the end openings, a' and c^2 , are closed on the revolving movement of the disk D by the said 95 slides passing alternately over the said openings a' and c^2 .

Having thus fully described my invention, I claim as new and desire to secure by Letters Patent—
100

1. In a rotary engine, the combination, with a revolving disk secured to the main driving-shaft and carrying two or more sets of cylinders, each set consisting of two cylinders placed diametrically opposite each other, of a piston-rod connecting the two pistons of a set of cylinders and a cross-head secured on each of the said piston-rods and provided with a slot extending at right angles to the said piston-rod, a fixed pin held eccentrically to 105 the center of the said disk and extending into the said slots of the cross-heads, a steam-chest formed on the bearing of the disk and provided with two live-steam ports, and a slide-valve held over the said two live-steam ports, 110 so that when one is opened the other is closed, whereby the engine can be reversed, substantially as shown and described.
115

2. In a rotary steam-engine, the combination, with a bearing provided with steam inlet ports and exhaust-ports, of a steam-chest formed on the said bearing, a valve held to slide in the said bearing over the said two ports, so that when one is open the other is closed, a disk held to rotate on the said bearing and secured to the main driving-shaft, 120 said disk being provided with ports adapted to register with the said steam inlet and outlet ports in the bearing, two or more sets of cylinders secured to the said disk, each set consisting of two cylinders placed diametrically opposite each other and connected with each other by a piston-rod carrying a cross-head, and a fixed pin held eccentrically to 125 130

the center of the said disk and adapted to engage the cross-heads of the said piston-rods, substantially as shown and described.

3. In a rotary engine, the combination, with
5 a bearing provided with inlet and outlet ports,
of a steam-chest formed on the said bearing
and into which open the said inlet-ports, a
valve held to slide over the said inlet-ports so
that when one is open the other is closed, a
10 disk held to rotate on the said bearing and
provided with channels adapted to register
with the said inlet and outlet ports, slides
held over the said channels so as to connect
the latter alternately with the respective in-
15 let and outlet ports, two or more sets of cyl-
inders held on the said disk and into which

open the said channels in the disk, each set
of cylinders consisting of two cylinders placed
diametrically opposite each other, a piston
held to slide in each of the cylinders, a 20
piston-rod connecting the two pistons of one
set of cylinders, a cross-head formed in the
middle of each piston-rod, each cross-head
being provided with a slot extending at right
angles to the piston-rod, and a fixed pin held
eccentrically to the center of the said disk
and extending into the slots of the said cross-
heads, substantially as shown and described.
